UNITED STATES PATENT OFFICE.

ADDISON R. SPAULDING, OF LAKE CITY, MINNESOTA.

RAILWAY-TIE.

SPECIFICATION forming part of Letters Patent No. 281,806, dated July 24, 1883.

Application filed March 24, 1883. (No model.)

To all whom it may concern:

Be it known that I, ADDISON R. SPAULDING, a citizen of the United States, residing at Lake City, in the county of Wabasha and State of Minnesota, have invented certain new and useful Improvements in Railway-Ties, of which the following is a specification, reference being had therein to the accompanying drawings.

This invention has relation to improvements in railway-ties; and it consists in the novel construction and arrangement, all as will be hereinafter more fully explained.

The annexed drawings, to which reference is made, fully illustrate my invention, in which Figure 1 represents a plan view of my device. Fig. 2 is a vertical sectional view of the same, and Fig. 3 is a cross-sectional view taken through line *y y*, Fig. 2.

Referring by letter to the accompanying drawings, A designates a railroad-tie constructed preferably of metal, having a longitudinal channel, *a*, extending the entire length, and in cross-section the tie is of I_{sh} form, thereby saving material in its construction, and at the same time affording a strong and durable tie. At each end and on the upper face the tie is provided with a transverse dovetail groove, *b*, in the bottom of which is seated a cushion, *c*, having bevel sides to correspond with the shape of the groove, as shown in the drawings. Upon this cushion *c*, and within the groove *b*, is seated the rail *d*, that is provided with notches *e* in each side on its base-flange to receive the pointed end *f* of a sliding latch-key, *g*, which latter is seated and slides within a longitudinal dovetail groove, *h*, on opposite sides of the groove *b*, as shown. Adjoining the said groove, and on opposite sides thereof, are formed shallow dovetail grooves *i*, to receive a wedge-key of metal, as at *k*, which is provided on one side with notches *l*, in which the point *m* of the sliding latch *g* engages. Within the said groove, and in rear of said wedge-key *k*, is placed a wooden wedge-shaped clamping-key, *n*, that binds and firmly secures the slide *g* and key *k* when the same are in position.

On the under side of the tie A, and directly beneath the rail seat or groove *b*, at each end thereof and within the channel *a*, I provide a recess, *o*, to receive a cushion, *p*, of any suitable material, whereby jarring or shock caused

by trains are alleviated when the tie is laid on a rigid foundation, but the cushions can be dispensed with when otherwise used.

It will thus be observed from the above description and by reference to the annexed drawings that in locking the rail to the tie the operation is very simple, and can be quickly done after the rail is seated upon the cushion and within the groove *b*. The slide-latch is placed in position, with its point *f* engaging the notch *e* in the rail, while the opposite point, *m*, enters the notch in the metal key *k*, after which the wooden wedge-key *n* is driven home and a spike or nail, *q*, driven in the narrow end, thereby preventing the wedge *n* from working loose by said spike coming in contact with the edge of the tie, as shown in the drawings. Again, it will be seen by reference to the drawings, I economize in material by taking off the edges and corners of the tie, and channel the same underneath, and yet preserve a strong and durable tie, and the packing material and wooden keys give sufficient elasticity to the rail to allow contraction and expansion due to atmospherical change.

The tie can be made any desirable size and of any suitable metal, cast whole or in sections and riveted together, galvanized or coated with other substance for preservation, and the rubber or other cushion may project somewhat beyond the sides of the tie. Furthermore, it will be noticed that my railway-tie is so constructed that by means of the clamping-wedges and slide-latch the rail is held firmly in place, the parts easily and quickly separated when desired to detach the rail from the tie, and at the same time is cheap to manufacture, and is light to handle.

Having described my invention, what I claim, and desire to secure by Letters Patent, is—

1. The combination, in a railway-tie channelled on its under side, forming I_{sh} shape in cross-section, and provided with recesses *o o*, to receive the cushion, and having on its upper face a transverse dovetail groove, *b*, in which is seated the cushion *c*, of the latch-keys *g*, wedge-keys *K*, and clamping-key *n*, sliding in dovetail grooves *h i*, formed on the upper face of the tie, as shown and described.

2. A railway tie provided on opposite sides of the rail-seat with dovetail transverse

grooves *i*, to receive clamping-wedges *k* *n*, and longitudinal dovetail grooves *h*, to receive the slide-latches *g*, whereby the rail is removably locked to the tie, as shown and described.

5 3. The combination, with the rail and tie having transverse grooves *i* and longitudinal grooves *h*, of the slide-latches pointed at both ends, one end to engage the notch *e* in the rail, and the opposite end to engage a notch in the

metal key *k*; the latter clamped against the slide by the wooden wedge *n*, as shown and described.

In testimony whereof I affix my signature in presence of two witnesses.

ADDISON R. SPAULDING.
